UNITED STATES PATENT OFFICE

ROY T. AXE, OF SYRACUSE, NEW YORK, ASSIGNOR TO THE O. M. EDWARDS COMPANY
INC., OF SYRACUSE, NEW YORK, A CORPORATION OF NEW YORK

WINDOW SASH AND GUIDE MEANS

Original application filed June 4, 1929, Serial No. 368,315. Divided and this application filed May 15, 1930. Serial No. 452,748.

This invention relates to window sash constructions and to guide means for window sashes which are particularly applicable for vehicles as railway cars, motor busses and the like. An object of the invention is to provide a sash construction and guide means which are rigid, light, and comparatively narrow and highly efficient and durable in use.

A further object of the invention is to provide a simple sash construction which will be weather-proof, and which will be free from rattles due to vibration of the railway car, motor bus, or the like.

The invention consists in the novel features and in the combinations and constructions hereinafter set forth and claimed.

In describing this invention, reference is had to the accompanying drawing, in which like characters designate corresponding parts in all the views.

Figure 1 is an elevation showing my improved sash construction and guide means, parts being broken away to more clearly indicate the arrangement.

Figure 2 is a section along the line 2—2 of Figure 1.

1 designates the sash.

2 designates the stiles or upright members; 3, 4 the bottom and top members or rails which are formed of sheet metal so that said members are hollow and of light weight.

The stiles and rails are formed in any suitable manner to provide a channel 5 which receives the margin of the pane 6, the margin of the pane being seated in a rubber channel 7, seated in the channel 5. One of the members or rails carries sash holder means, as the sash here shown is designed to be lowered into a well beneath the sill. The sash holder means are carried by the top rail 4.

The sash holder means designated generally as 11 are of the type shown in the parent application, Sr. No. 368,315, a latch bolt 8 projecting beyond the edges of the sash coacting with the upper part of the window guide to hold the sash in any desired position. These latch bolts are operated by the sash holder means 11, but since this forms no part of the present invention, a description of the operating mechanism which was described in

the parent application, Sr. No. 368,315, is unnecessary.

40 and 41 designate outer and inner opposing sections of the sill construction, these being spaced apart to form a slot 42 through which the sash slides. These sections are formed with overhanging portions 43 and 44 respectively, and the overhanging portion 43 is provided by the metal sheeting 45 of the outer section 40.

The sash guides 10 extend above the slot 42 and the guides 46 extend below the slot 42. The bottom rail 3 of the sash is formed with the weather strip 47 along the bottom edge which coacts with said overhanging portions 43 and 44, the weather strip extending beyond the inner and outer faces of the bottom rail and having an upturned flange 48 at its outer edge extending between the outer face of the bottom rail 3 and the inner edge of the overhanging portion 43 of the outer section 40 of the sill so as to form a weather tight joint when the sash is closed. There is a depending window guide 46 at each side of the sash, and each of these guides is in the form of a channel for receiving the stiles 2 of the sash when the sash is open.

The sides of each channel 46 flare outwardly toward the upper ends to guide the sash therein. Each guide 46 is also provided with one or more compression devices for pressing against the stiles and holding the sash from rattling when the sash is lowered below the sill. Each compression device, as here illustrated, comprises a shoe 50 extending through a slot 51 in one side wall of each channel 46, the shoe having lugs 52 at its ends overlapping the outer sides of the slot 51, and these lugs are provided with openings which slidably receive studs 53 secured at like ends in one of the side walls of the channel 46 and at their outer ends in an offset frame or brace strip 54 carried by one of the side walls of the channel 46. Compression springs 55 encircle the studs 53 and thrust against the ends of the shoe 50 and against the offset portion of the strip 54.

The sash, when closed, occupies the positions shown in Figures 1 and 2 with respect to the window frame. To lower the sash, the

operator takes hold of the sash holder means 11 withdrawing the latches 8 from the upper frame and either lets the sash drop, or lets it down gently into the wall or guides 46 below the sash. The compression device or shoe 50 prevents violent dropping of the sash.

While I have shown the preferred embodiment of my invention, various changes and modifications may be made without departing 10 from the scope of the invention as set forth in the appended claim.

What I claim is:

In a window construction, the combination 15 of a window frame including a sill construction formed with a slot, and guides above and below the slot, a sash movable in the guides, the sill construction being formed with flanges projecting toward the sash and overhanging the guides below the sill, a weather 20 strip overlying the lower edge of the bottom rail and having an angular portion at one edge thereof extending upwardly along one of the upright faces of the bottom rail and entering the space between one of the overhanging portions of the sill and the bottom rail, the weather strip also having a portion 25 extending beyond the opposite upright face of the bottom rail into position to hook under the other overhanging portion of the sill, 30 whereby when the sash is raised into closed position, the crevices between the bottom rail and the overhanging portions are closed by said weather strip.

In testimony whereof, I have hereunto 35 signed my name at Syracuse, in the county of Onondaga, and State of New York, this 14th day of May, 1930.

ROY T. AXE.
